UNITED STATES PATENT OFFICE

CHAUNCEY MATLOCK, OF NEW YORK, N. Y., ASSIGNOR TO GASOLINE CORPORATION, OF NEW YORK, N. Y., A CORPORATION OF DELAWARE

AUTOMATIC OIL-PUMP REGULATOR

Application filed February 25, 1921, Serial No. 447,865. Renewed March 29, 1929.

The present invention relates to the treatment of hydrocarbon oils and more particularly to an apparatus for providing a continuous control of the temperature and other factors governing the cracking of heavy hydrocarbons for the production of low boiling hydrocarbon liquids, particularly in continuous processes of the type disclosed in Greenstreet Patent 1,110,924.

10 In the transformation or cracking of heavy hydrocarbons to form light hydrocarbon liquids, the degree of cracking and the products produced are governed very largely by the temperature conditions under which the transformation is carried out. Thus, too high a cracking temperature produces an excessive quantity of gas and a correspondingly low yield of the desired products, while treatment at too low a temperature does not 20 produce a sufficient quantity of the desired products.

The temperature at which the transformation or cracking is carried on is determined very largely by the temperature of the furnace or other means used for heating the oil, and in continuous processes for which the present invention is particularly suited, is also directly controlled within certain limits by the rate at which the oil is passed thru 25 the heating apparatus. Thus, if a given temperature is maintained in the furnace, the temperature to which the oil is heated and the quantity of heat supplied to the oil may be varied by increasing or decreasing the 30 quantity of oil supplied to the treating apparatus, a lower temperature, of course, being obtained when the supply of oil is increased.

An object of the present invention is to 40 provide a method of controlling the temperature in oil treating processes in which an increase in temperature above a definite limit or a fall in temperature below a definite limit is avoided.

45 Another object of the present invention is to provide an apparatus for controlling the temperature and other conditions in oil treating processes by which the conditions of treatment of the oil are automatically maintained 50 within definite limits.

With these and other objects in view, the invention consists in the method and apparatus described in the following specification and defined in the claims.

The various features of the invention are 55 illustrated in the accompanying drawings in which:

Fig. 1, is a perspective view partly in section of the preferred embodiment of the present invention showing the relation of the controlling apparatus to the oil treating apparatus, and 60

Fig. 2, is a diagrammatic sketch partly in section showing in detail the controlling mechanism. 65

In the specific embodiment of the invention illustrated in the accompanying drawings, the invention is disclosed as applied to an apparatus for carrying on the process described in Greenstreet Patent No. 1,110,924. 70 In this process, the oil to be treated is mixed with steam and passed thru a coil or a number of coils of pipe, positioned in a furnace which is heated to a bright red temperature by means of gas or fluid fuel burners or other heating means positioned at some distance below the coils. The desired cracking reactions are obtained while the oil is being passed thru the heated coils and upon leaving the coils, the oil is immediately 75 chilled by contact with jets of water or other cooling fluid injected directly into the hot oil vapors. In the normal operation of the process, the furnace is kept at as even a temperature as possible, and the quantity of oil supplied to the treating coils is controlled to obtain a given temperature and heat treatment of the oil during its passage thru the coils. 80

In the present invention, the supply of oil to the treating coils is governed or controlled by the temperature of the oil as it leaves the treating coils to maintain the oil within certain temperature limits within which the desired transformation of oil is obtained. If 90 the temperature of the oil falls to the lower temperature limit, the rate of supply of oil to the heating coils is automatically decreased by decreasing the supply of steam or energy to the oil supply pump or other source of oil 95 100

supply, while if the oil rises to the upper temperature limit, the rate of supply of oil is increased by increasing the supply of energy to the apparatus for supplying oil to the coils.

5 Referring more particularly to the accompanying drawings, a supply of oil is withdrawn from a source of supply thru a pipe 10 by means of a pump 12 and is forced by the pump thru a supply pipe 14 to a header 16 from which it is distributed to a number of branch pipes 18 leading to corresponding heating coils. The quantity of oil supplied thru each branch pipe is controlled by means of valves 20 and the rate of supply observed by means of meters 22 inserted in the pipes 18. From the meters 22, the oil passes thru connecting pipes 24 to a number of treating coils 26 positioned within a furnace 28. A quantity of steam is supplied from a steam header 30 to each of the pipes 24 thru corresponding steam pipes 32 and control valves 34, the pressure of the steam being measured by means of a steam gauge 36 connected to the header 20. The steam is mixed with the oil in the pipes 24 and in the passage of the oil thru the coils 26, serves to prevent the oil from adhering to the inner walls of the coils and burning to form free carbon and from depositing carbon on the inner walls of the coils. Each portion of the oil passes thru the coil at a uniform rate and is subjected to the high temperatures prevailing in the furnace for a definite period of time. For any particular size of coil, the rate of passage of the oil and the time of its treatment is controlled by the rate of supply of oil to the coil—an increased velocity and a shorter period of treatment resulting from an increase in the quantity of oil supplied. From the coils 26, the treated oil or oil vapors pass thru connecting pipes 38 to a cooling header 40 into which jets of cooling water are injected thru inlet pipes 42. The hot oil vapors coming into direct contact with the jets of water are instantly chilled by the evaporation of the water and the further cracking of the oil thereupon ceases. The chilled oil passes from the cooling header 40 thru a vapor pipe 44 and a pressure release valve 46 to a condenser not shown. The pressure of the oil is measured by means of a pressure gauge 47 positioned within a control house 48 and connected to the vapor pipe 44 by means of a connecting pipe 49. The opening of the valve 46 is adjusted by the control house operator to maintain the desired pressure in the pipe 44 and gauge 47 by means of a valve spindle 50 extending into the control house.

63 The coils 26 are heated to the proper temperature by means of gas or other fluid fuel supplied to the lower part of the furnace 28 thru a number of fluid fuel burners 51 or may be heated by means of coal or other solid fuel.

65 The products of combustion pass upwardly in contact with the coils 26 and are exhausted

thru a number of openings 52 into a central flue 53 from which they pass to a smoke stack 54. The temperature of the furnace is maintained as uniform as possible thruout by adjusting the supply of fuel thru the burners 51 and adjusting the position of dampers 55 in the openings 52.

75 The temperature to which the oil is treated in each coil is measured by means of thermocouples 56 positioned in the pipe 38 connecting the coils to the cooling header 40. Each of the thermocouples 56 is connected thru leads 58 passing thru a suitable conduit 60 to a switch board 62. Each of the thermocouples may be separately connected to a galvanometer 64 by depressing an appropriate switch 66 in the switch board 62. Thru this arrangement, the control house operator may at any time obtain an accurate knowledge of the temperature to which the oil in any coil 85 has been treated.

95 The valves 20 in the pipes 18 are adjusted in accordance with the temperatures indicated by the thermocouples 56 and the galvanometer 64 to supply equal quantities of oil to each of the coils 26 and to thereby insure an equal heat treatment thruout all of the coils. To guard against variations in the temperature of treatment of the oil beyond limits within which the desired reactions are obtained, and particularly to guard against too high a temperature, a second galvanometer is provided which is at all times connected to all of the thermocouples and which, in turn, serves to 100 control or govern the rate of supply of oil to the cracking coils. Thus, if for any reason the rate of supply of oil should begin to decrease, a corresponding increase in the temperature of the treatment would result and the controlling galvanometer would immediately act to correct this action. If the temperature of the furnace should increase beyond that normally provided for, the tendency to heat the oil too high would also be 110 counteracted to a certain extent by the action of the controlling thermostat in increasing the supply of oil. In the embodiment of the invention illustrated in the accompanying drawings, the controlling galvanometer acts 115 to automatically correct the temperature variations in the treatment of the oil by increasing or decreasing the supply of steam to the pump 12, if the temperature of the oil undergoing treatment falls below or rises above the 120 limits of treatment.

125 To this end, the thermocouples 56 are connected, as shown diagrammatically in Fig. 2, thru connecting leads 66 to a controlling galvanometer 68 having a needle or pointer 70 130 the position of which is governed by the temperature of the thermocouple in contact with the hottest oil. If the temperature of any thermocouple should reach the upper limit for which the galvanometer is adjusted, the 130

needle 70 is deflected to the left until it contacts with a stop 72. An electric circuit is thereupon closed between a battery 74 connected to the pointer 70 thru a wire 76, in such a manner as not to affect the coil of the galvanometer or the movement of the needle, and thru branch circuit 78 connected to the stop 72 to a return circuit 80 and solenoid 82.

If the temperature of the thermocouples should fall to the lower limit for which the galvanometer 68 is adjusted, the needle 70 is deflected to the right until it contacts with a second stop 84 which is in turn connected thru a branch circuit 86 and solenoid 88 to the return wire 80. In this manner, if the pointer or needle 70 contacts with the stop 72 or the stop 84 in accordance with the temperature of the thermocouples, an electric current is passed thru the solenoid 82 or the solenoid 88 and these solenoids are accordingly energized to operate the controlling device for the admission of steam to the pump 12.

The admission of steam to the pump 12 is controlled thru a control valve operated by a diaphragm which is actuated in one direction by the pressure of compressed air, or other fluids under pressure admitted from a supply pipe 90 to one face of the diaphragm and is operated in the opposite direction by a spring bearing against the other face of the diaphragm when the pressure of the fluid is decreased. The admission of compressed air to the diaphragm from the supply pipe 90, is controlled by a valve 92 having a stem extending into the solenoid 88 and forming a core therefor. The valve 92 is raised and opened thru the magnetization of its stem when the solenoid 88 is energized and is permitted to fall and close the valve when the solenoid is deenergized. To insure a very slow admission of the air and to avoid rapid changes in the rate of supply of steam, a bleed valve 94 is provided thru which the rate of passage of air may be adjusted. When the valve 92 is open, therefore, a supply of compressed air is slowly sent from the pressure supply pipe 90 thru the valves 94 and 92 to a chamber 96, one side of which is closed by a movable diaphragm 98. As the compressed air is admitted to the chamber 96, the diaphragm 98 is forced downwardly against the action of a spring 100 inserted between the under-face of the diaphragm and a support 102. As the diaphragm moves downwardly it carries with it a valve spindle 104 on the lower end of which is mounted a valve or set of balanced valves 106 positioned in a valve chamber 108 thru which steam passes from a supply pipe 110 to the pump 12. As the valves 106 move downwardly they approach valve seats 112 and restrict the passage of steam from the pipe 110 to the pump 12. The action of the pump is thereby retarded and a smaller quantity of oil is supplied thru the pipe 16 and branch pipe 18 to the coils 26 and as a result,

the temperature of the treated oil rises. The admission of compressed air to the chamber 96 continues until the temperature of the oil coming in contact with the thermostats 56 reaches a point at which the needle 70 of the galvanometer 68 is deflected to the left out of contact with the stop 84 and interrupts the circuit thru the solenoid 88. The solenoid is thereby deenergized and the valve 92 falls to a closed position and stops the further passage of pressure fluid to the chamber 96 and diaphragm 98.

If the temperature of the oil continues to rise until it reaches a point corresponding to that at which the stop 72 is placed on the temperature scale of the galvanometer, the needle 70 coming into contact with the stop 72 closes the branch circuit 78 thru the solenoid 82. As the solenoid 82 is energized it raises a valve 114 having the same relation to the solenoid 82 as the valve 92 has to the solenoid 88. The valve 114 is arranged to control the escape of fluid from the chamber 96 thru an escape pipe 116, the valve being opened when drawn into its upper position by the second solenoid 82. A bleed valve 118 may also be provided to control the rate of escape of fluid. As the fluid escapes from the chamber 96, the diaphragm 98 is forced upwardly by the action of a spring 100 and draws the valve 106 away from the valve seats 112, thus, permitting a greater supply of steam to the steam chamber of the pump 12. A corresponding supply of oil is thereupon forced into the coils 26 and the temperature of treatment of the oil is accordingly lowered.

A hand controlled valve 120, Fig. 1, is provided to control the admission of steam to the pump 12. In starting the device, the control valves 106 are opened inasmuch as the thermostats are at substantially atmospheric temperatures and the controlling mechanism only comes into effect after the oil has been heated to the cracking temperature.

Having described the invention, what is claimed as new is:

1. An apparatus for treating hydrocarbon oils which comprises a furnace, treating pipes in said furnace, a pump arranged to supply oil to said pipes, temperature measuring means in the outlet ends of said pipes, a diaphragm, means controlled by said diaphragm for regulating the speed of said pump and means controlled by the temperature of the oil issuing from each of said pipes for admitting fluid under pressure to or for withdrawing fluid from said diaphragm.

2. An apparatus for treating hydrocarbon oils which comprises a furnace, treating pipes in said furnace, means for supplying oil to said pipes, means for measuring the temperatures to which said oil is treated in each of said pipes, means for controlling the distribution of oil to said pipes and means for automatically increasing or decreasing the sup-

ply of oil to said pipes as the temperature of treatment of said oil increases to or falls to definite temperature limits in any one of said pipes to control the temperature of the oil in said pipes.

- 5 3. An apparatus for treating hydrocarbon oils which comprises a furnace, treating pipes in said furnace, means for supplying oil to said pipes, means for controlling the distribution of oil to said pipes, thermocouples arranged to measure the temperature of the oil from each of said pipes, a controlling galvanometer and means controlled by said galvanometer to increase or decrease the supply of oil to said pipes when the temperature of oil from said pipes reaches definite temperature limits in any one of said pipes to control the temperature of the oil in said pipes.

- 10 4. An apparatus for treating hydrocarbon oils which comprises a number of pipes, means for heating said pipes, an oil pump, means for distributing oil from said pump to said pipes, means for controlling the distribution of oil to said pipes, means for measuring the temperature of treated oil issuing from each of said pipes and means governed by said temperature measuring means to control the speed of said pump to maintain said temperatures within definite limits.

- 15 30 5. In apparatus for treating hydrocarbon oils including a treating pipe, means for heating said pipe, and a pump for supplying oil to said pipe a control mechanism for said pump, said mechanism including a thermocouple positioned to measure the temperature of the oil in said pipe, a galvanometer connected to said thermocouple, an electric circuit having branches, a solenoid in each of said branches, said galvanometer being arranged to close one of said branches when the temperature of said thermocouple reaches a maximum limit and to close the other of said branches when thermocouple reaches a lower limit, a steam supply to said pump, a diaphragm arranged to control the supply of steam to said pump and means governed by one of said solenoids to admit fluid under pressure to said diaphragm and by the other of said solenoids to control the escape of fluid from said diaphragm.

- 20 45 55 60 65 6. In an apparatus for treating hydrocarbon oils which comprises a plurality of pipes adapted to be heated, means for supplying oil to said pipes; means for measuring the temperature of oil issuing from each of said heated pipes; and means for automatically varying the supply of oil to said pipes in accordance with variation of temperature in the oil issuing from any one of said pipes.

- 60 65 In testimony whereof, I affix my signature.

CHAUNCEY MATLOCK.
